UNITED STATES PATENT OFFICE.

JOHN W. DARLEY, JR., OF BALTIMORE, MARYLAND.

PROJECTILE AND MEANS FOR FIRING SAID PROJECTILE.

1,344,992.

Specification of Letters Patent. Patented June 29, 1920.

Application filed May 12, 1915. Serial No. 27,617.

To all whom it may concern:

Be it known that I, JOHN W. DARLEY, Jr., a citizen of the United States, residing at Baltimore, in the State of Maryland, have 5 invented certain new and useful Improvements in Projectiles and Means for Firing Said Projectiles, of which the following is a specification.

My invention relates to improvements in 10 projectiles and means for firing same.

Heretofore, projectiles, when fired at a submarine boat, have ricochetted and unless they struck the periscope of the boat, the latter has escaped injury.

15 I have discovered that if a projectile is given a motion of rotation as herein described, it will not ricochet but will plunge downward and can be made to reach the hull of a submarine boat.

20 Since the hull of said boat is comparatively small, the danger area is small. For this reason, I provide a projectile that explodes when its speed of rotation is altered a predetermined amount and accomplish

25 this result by a specially constructed fuse, which is the subject of an application for Letters Patent of even date herewith. Said explosion occurs whether said alteration of said speed is due to the resistance of the

30 water, or to the projectile striking said boat.

Hence I can produce explosions against the hull of said boat, or near thereto, and thus greatly increase the chances of injury to said boat.

35 The objects of my invention are:—

To produce a projectile having such a shape and such a movement that it will plunge under the water when fired at a submarine boat.

40 To produce a gun for firing said projectile in such a manner as to give to said projectile a motion to prevent the ricochetting of said projectile.

In the drawings:—

45 Figure 1 is a longitudinal section of one form of my improved gun taken along the line 1—1 of Fig. 2, looking in the direction of the arrow;

Fig. 2 is a view of the muzzle end of said 50 gun;

Fig. 3 is a fragmentary, longitudinal section of said gun along the line 3—3 of Fig. 2, looking in the direction of the arrow;

Fig. 4 is a front view of one form of my 55 improved projectile;

Fig. 5 is an enlarged sectional view of same along the line 9—9 of the projectile shown in Fig. 1, looking in the direction of the arrow;

Fig. 6 is a side view of a second form of 60 my improved projectile;

Fig. 7 is a view of the projectile shown in Fig. 6 looking in the direction of the arrow;

Fig. 8 is a view showing the approxi- 65 mately observed course of my improved projectile in the water;

Fig. 9 is a longitudinal section of another form of my improved gun taken along the line 14—14 of Fig. 10, looking in the direc- 70 tion of the arrow;

Fig. 10 is a view of the muzzle end of said gun;

Fig. 11 is a fragmentary longitudinal section of said gun along the line 16—16 of 75 Fig. 10, looking in the direction of the arrow;

Fig. 12 is a front view of a third form of my improved projectile;

Fig. 13 is an enlarged section along the 80 line 18—18 of the projectile shown in Fig. 9, looking in the direction of the arrow;

Fig. 14 is an enlarged front view of my 85 improved projectile; and

Fig. 15 is a view showing my projectile in water with arrows indicating the direc- 85 tions of movements.

Fig. 16 is an enlarged view of the muzzle end of the gun as shown in Fig. 10.

In the drawings, 30 indicates a gun barrel 90 which may be of any suitable material and shape, mounted in any approved manner and provided with a breech block 31 permitting of the introduction of the projectile 32 and powder charge 33.

The gun 30 is provided with a cylindrical bore 34, with a slot 35 at the top of said bore, and with dentations 36 at the bottom thereof.

One form of my improved projectile 32 is 100 shown in Figs. 4 and 5. It is spherical in form and provided with a zone of dentations 56 which are adapted to mesh with the dentations 36 and be guided by the groove 35.

The projectile 32 is further provided with a fuse 57, which may be of any suitable type and construction, and with an interior boss 58 adapted to fit around the fuse 57 to support it during the shock of firing. A 110

balancing boss 59 is provided opposite the fuse 57, and by drilling the hole 60 to various depths a perfect balance is obtained.

The interior 61 is to be filled with a high power explosive.

The second form of my improved projectile shown in Figs. 6 and 7 is similar to that shown in Figs. 4 and 5 except that the zone of dentations 56 is omitted and the 10 projectile is first made spherical in form and teeth such as 62 are cut in said projectile.

In the other form of my improved gun, shown in Figs. 9, 10 and 11, 63 indicates 15 a gun barrel arranged in all respects the same as the gun barrel shown in Figs. 1, 2 and 3, except that the groove 64 in the former, is shallower than the groove 35 in the latter, and that in the former the dentations 65 are approximately parallel with the axis of the gun.

The dentations 65 are formed as follows:—Two grooves 66 and 67 are cut in the gun barrel parallel with the axis thereof 25 (see Fig. 16), and having the faces 68 and 69 parallel with each other and with a plane passed through said axis and the line 14, 14. The faces 68 and 69 are the same distance apart as the faces 70 and 71 of the groove 30 64, which are also parallel with each other and with said plane. The grooves 66 and 67 extend from the breech to the muzzle.

The faces 72 and 73 of the teeth 74 and 75 are next cut and these faces are one eighth 35 of an inch closer together at the muzzle end of the gun than at the breech.

The grooves 76 and 77 are next cut, and these grooves are one eighth of an inch closer together at the muzzle end of the gun 40 than at the breech.

The groove 78 is next cut, and it is one eighth of an inch narrower at the muzzle end of the gun than at the breech. There are thus formed four teeth which 45 extend from the breech to the muzzle of the gun. The pair of teeth 74 and 76^a are parallel to each other; and the pair of teeth 75 and 77^a are parallel to each other, but the first pair of teeth is one eighth of an inch 50 closer to the second pair of teeth at the muzzle of the gun than at the breech. The portions of the teeth 74, 75, 76^a and 77^a which extend from the breech block to a point just in front of the projectile 79 are 55 then removed, thus providing a groove between the faces 68 and 69 in all respects similar to the upper groove between the faces 70 and 71. The lower groove is provided so that the projectile may be readily 60 placed in the bore of the gun.

For use with this type of gun the projectile shown in Figs. 9, 10, 12, 13 and 14 is preferred. Said projectile consists of the spherical body 79 having a groove 80 therein 65 in which is shrunk a copper zone 81. In

all other respects said projectile is similar to the projectile shown in Figs. 1, 2, 4 and 5.

The operation of the gun shown in Figs. 1, 2 and 3, and the projectile shown in Figs. 1, 2, 4 and 5 is as follows:—

When the charge 33 is fired the projectile 32 will be moved along the gun bore, but by reason of the interaction of the dentations 36 in the gun bore and the dentations 56 on the projectile 32, the latter will be 75 caused to revolve in the direction of the arrow 82 in Figs. 1, 8 and 15.

The projectile shown in Figs. 6 and 7 is to be fired from a smooth bore gun and the action of the gases on the teeth 62 will give 80 the projectile a rotation in the direction of the arrow 82 in Fig. 6.

Similarly the projectile shown in Figs. 9, 10, 12, 13 and 14 will be given a rotation in the direction of the arrow 82 in Fig. 9, 85 when fired from the gun shown in Figs. 14, 10 and 11, because the copper zone 81 will have grooves cut therein by the teeth 65. Since these teeth 65 have inclined faces, and the pairs of teeth are inclined to each other, 90 a continuous gripping action will obtain between said teeth and the zone 81 while the projectile is in the bore of the gun.

The projectile shown in Figs. 9, 10, 11, 12, 13 and 14 may be also fired from a gun 95 constructed as shown in Figs. 1, 2 and 3, but having the depressions 53 and groove 35 cut shallower. When so fired said projectile will also be rotated in the direction of the arrow 82 in Fig. 1.

When either of the different forms of projectiles is fired and rotated in the direction of the arrow 82, it moves through the air in the direction of the arrow 83, along the trajectory 84 (see Fig. 8). When the projectile strikes the water it will move for a short distance in the direction of the arrow 85 (see Fig. 15), and then by reason of the combined effect upon the water of the motion in the direction of the arrow 85 and 110 the rotation in the direction of the arrow 82, a lateral pressure is developed in the direction of the arrow 86 (see Fig. 15), which forces the projectile through the water along the approximately observed 115 path 86^a shown in Fig. 8.

Thus by firing and rotating my improved projectile as just described, I am enabled to effectually prevent ricochetting of the same when it strikes the water. It is evident that since this effect is due only to a reaction between the projectile and water, it is independent of range, form of trajectory or velocity of the projectile.

If for any reason it is desirable to cause 125 the projectile to ricochet, this can be easily accomplished by turning the guns shown in Figs. 1 and 9, or the projectile shown in Fig. 6, on their axes through an angle of 180 degrees to reverse the direction of ro- 130

tation, when a lateral pressure will be developed in the direction of the arrow 87 (see Fig. 15), which forces the projectile out of the water along the approximately 5 observed path in Fig. 8.

I claim:—

1. The combination with a gun having a bore, of a wall surrounding said bore and a plurality of means formed in the wall of 10 said gun below the surface of said bore for rotating a projectile around an axis at right angles to the axis of said gun.
2. The combination with a gun barrel having a bore and an imperforate wall surrounding said bore, of means formed in said wall on one side of said bore for retarding the adjacent portion of a projectile. 15
3. The combination with a gun of means formed in one side of the bore of said gun 20 for retarding the adjacent portion of a projectile and means formed in the opposite side of said bore for guiding said projectile.
4. The combination with a gun having a bore and a projectile guided by said bore, of 25 dentations on one side of the bore of said gun and means on said projectile for coöperating with said dentations to rotate said projectile.
5. The combination with a gun and projectile, of dentations on one side of the bore 30 of said gun and means on said projectile for coöperating with said dentations to rotate said projectile and a groove on the opposite side of said bore coöperating with said 35 means to guide said projectile.
6. The combination with a gun and projectile, of dentations mutually inclined and extending longitudinally on one side of the bore of said gun and means on said projectile for coöperating with said dentations 40 to rotate said projectile.
7. The combination with a projectile, of a gun barrel having a bore and an imperforate wall surrounding said bore, of means 45 formed in said wall on one side of said bore for retarding the adjacent portion of said projectile.
8. The combination with a projectile, of a

gun having a bore for guiding said projectile, a wall surrounding said bore and 50 means formed in said wall on one side of said bore for rotating said projectile around an axis at right angles to the axis of said gun, the speed of rotation of the periphery of said projectile having a fixed ratio to the 55 linear speed of said projectile along the bore of said gun.

9. In a gun, the combination with a bore and an imperforate wall surrounding said bore, of dentations on one side of said bore. 60

10. In a gun, the combination with a bore, of dentations on one side of said bore and a groove on the opposite side of said bore.

11. In a gun, the combination with a cylindrical bore and an imperforate wall surrounding said bore, of dentations on one side 65 of said bore.

12. In a gun, the combination with a cylindrical bore, of dentations on one side of said bore and a groove on the opposite side 70 of said bore.

13. The combination with a gun, of a spherical projectile having a zone of malleable metal around the body thereof, said zone of metal coöperating with said gun to 75 rotate said projectile on an axis at right angles to the axis of said gun.

14. The combination with a gun, of a spherical projectile having a zone of malleable metal surrounding said projectile, the 80 edges of said zone projecting beyond the surface of said projectile, said zone of metal coöperating with said gun to rotate said projectile on an axis at right angles to the axis of said gun. 85

15. The combination with a gun having a bore, of an imperforate wall surrounding said bore and a plurality of dentations formed in said wall below the surface of 90 said bore for rotating a projectile. 90

In testimony whereof I affix my signature in presence of two witnesses.
